CONDENSER FOR LONG DRAFT SPINNING

Richard R. Pope, Sylacauga, Ala., assignor to
Avondale Mills, a corporation of Alabama

Application December 22, 1947, Serial No. 793,073

9 Claims. (Cl. 19—130)

1

This invention relates to a condenser for use in the attenuation of fibers on a spinning frame, and particularly for use in a long draft spinning system wherein the sliver or roving is subjected to repeated draft without twist. In such spinning systems it has been found desirable to subject the sliver to a condensing or folding operation between successive sets of drawing rolls in order to control the fibers and prevent their spreading and tangling. Various forms of condensers have been proposed for this purpose, all of those with which I am familiar embodying complex convolutions, difficult to form in the manufacture thereof.

It is accordingly the prime object of my invention to provide a condenser of the character described which is simple of design, easy of manufacture and reliable in operation.

I have found that if the sliver be passed through a condenser presenting to the sliver first a surface inclined to the vertical, followed by a surface substantially vertical, the fibers comprising the sliver will be folded over to the extent that a false twist is placed therein from the condenser back to the next preceding pair of drawing rolls, thereby effectively controlling the fibers and preventing spreading and tangling. Preferably, my improved condenser is placed as close as possible to the nip of the succeeding pair of rolls and above the line of direction between the nips of the pairs of rolls with which it is associated. The fibers are thus restrained against separating throughout their travel from one pair of drawing rolls to the next.

Apparatus embodying features of my invention is illustrated in the accompanying drawing forming a part of this application in which:

Fig. 1 is a diagrammatic view of a long draft spinning system in which my improved condenser is installed:

Fig. 2 is a plan view, with the top rolls removed, and looking in the direction of the arrows II-II of Fig. 1;

Fig. 3 is a side view of the condenser removed from the spinning frame, and drawn to a larger scale;

Fig. 4 is a front view of the condenser:

Fig. 5 is a fragmental plan view of the condenser drawn to a further enlarged scale:

Fig. 6 is a side view of a modified form of my 50 improved condenser:

Fig. 7 is a front view of the condenser shown in Fig. 6; and

Fig. 8 is a plan view thereof.

Referring to the drawing for a better understanding.

1

standing of my invention, I show in Fig. 1, a rear group of drawing rolls A and a forward group B. Group A comprises a pair of feed rolls 18 and 19 and a pair of drawing rolls 21 and 22, and a second pair of drawing rolls 23 and 24. Surrounding the rolls 21 and 22 and extending forwardly therefrom, as shown, are endless flexible bands 26 and 27, formed of rubber or the like. The forwardly extending loops of the bands are supported in frames 28 and 29, in a manner well understood in the art.

The group of rolls B comprises a pair of drawing rolls 31 and 32 and a second pair of drawing and discharge rolls 33 and 34. Surrounding the rolls 31 and 32 are endless bands 36 and 37, similar to the bands 26 and 27, and having the forwardly extending loops thereof supported in frames 38 and 39. A sliver S is fed to the group of rolls A over a rod 42 and through a trumpet 20 44 mounted on a traverse bar 43.

The sliver is delivered from the rolls 23 and 24 of group A to the rolls 31 and 32 of group B. Mounted on a traverse bar 46 between the rolls 23-24 and the rolls 31-32 is my improved condenser indicated generally by the numeral 41, which will now be described. In the form of my invention shown in Figs. 1 to 5, the condenser is made of wire and is provided with a shank 48 having an eye 49 formed therein to receive a securing bolt 51. The shank 48 extends vertically and is laterally offset with respect to the line of travel of the sliver S. At its upper end it is bent laterally as shown at 52 and then downwardly inclined as shown at 53. At the lower end of the inclined

35 portion 53 the end of the wire is turned upwardly to provide a substantially vertical portion 54 which is directly forward of the bottom of the V notch formed with the inclined portion 53. The sliver S is thus first engaged by the inclined portion 53 which causes a folding over of the fibers as indicated at 56 in Figs. 1, 2 and 5 to the extent that a false twist is placed therein, which extends rearwardly to the nip of the pair of rolls 23 and 24, and is then engaged by the vertical portion 54, offsetting slightly the line of travel of the sliver. The engagement of the sliver by the vertical portion 54 holds the false twist in the fibers until the sliver leaves the condenser. Thereafter there is no twist in the sliver as it 40 enters the nip between the rolls 31 and 32. It will be noted from Fig. 3 of the drawing that the forward inclination of the wire forming the condenser permits the V notch formed by the sides 45 53 and 54 to be positioned closely adjacent the nip of the rolls 31 and 32. It will also be noted

that the lateral offset of the shank 43 from the laterally inclined portion 53, permits a workman to reach down between the rolls 23-24 and 31-32, to place the sliver S in the notch.

In Figs. 6, 7 and 8, I show a modified form of my invention in which my improved condenser is formed from a metal plate bent to shape to provide a V notch 61. The V notch is formed by an upwardly disposed side 62 inclined to the vertical and an upwardly disposed, substantially vertical side 63. The sides converge from rear to front of the condenser. Adjacent the forward end 64 of the condenser, the inclined side 62 is provided with a rounded bead or projection 66, disposed to lie inwardly of the V notch thereby assuring that the sliver will contact the inclined side first. Also, the forward end 64 of the inclined side and the bead 66 are downwardly inclined from rear to front with respect to the direction of approach of the sliver, as shown in Fig. 8. The forward end 67 of the vertical side 63 extends past the bead 66 and lies substantially directly forward of the bottom of the V notch 61. The end of the vertical side preferably is rounded as indicated at 68 and lies in a vertical plane which is substantially normal to the axes of the rolls. The condenser is provided, as usual, with a supporting shank 19 for attaching to the traverse bar 46.

With either form of my invention the sliver is first engaged by the inclined surface of the condenser and next by the substantially vertical surface. The rounded surfaces 66 and 68 engaged by the sliver provide only a line contact, thereby greatly reducing friction, and offering a minimum of resistance to twisting. I have found that the amount of false twist placed in the sliver by the action of the condenser is determined, within limits, by the inclination of the inclined portion 53 or 62 as the case may be, the greater the inclination, the greater the amount of false twist. I have found that my improved condensers are equally effective with fine roving as with coarse; also with double creel roving. With the latter, the strands are placed together and blended to pass between the rolls.

Although I have shown only one condenser and that placed between the rolls 23-24 and 31-32, it will be apparent that a condenser may be placed between each of successive pairs of drawing rolls. In fact, I have found that where the sliver is being drawn to finer numbers, it is advisable to employ more than one condenser.

From the foregoing, it will be apparent that I have developed an improved condenser for use in spinning frames which is simple of design, easy of manufacture, and effective in operation.

While I have shown my invention in but two forms, it will be obvious to those skilled in the art that it is not so limited, but is susceptible of various changes and modifications, without departing from the spirit thereof, and I desire, therefore, that only such limitations shall be placed thereupon as are specifically set forth in the appended claims.

What I claim is:

1. The combination with long draft fiber attenuating apparatus embodying a plurality of pairs of drawing rolls, of a condenser interposed between two successive pairs of rolls comprising a member having a V-shaped notch therein with one side of the V lying in a plane which is substantially normal to the axes of the rolls and the other side of the V inclined to said plane, a portion of the side of the V which is substantially normal to the axes of the rolls being dis-

posed rearwardly of the inclined side with respect to the direction of approach of the sliver and in position for the sliver to engage the inclined side and said portion of the side which is substantially normal to the axes of the rolls.

2. The combination with long draft fiber attenuating apparatus embodying a plurality of pairs of drawing rolls, of a condenser interposed between two successive pairs of rolls comprising a member having a V shaped notch therein with one side of the V lying in a plane which is substantially normal to the axes of the rolls and the other side of the V inclined to said plane, the inclined side being so disposed as to first engage the sliver and the side which is substantially normal to the axes of the rolls being directly rearward of the inclined side with respect to the direction of approach of the sliver.

3. Apparatus as defined in claim 2 in which the condenser is formed from a metal plate shaped to provide the V notch.

4. Apparatus as defined in claim 2 in which the condenser is constructed of wire bent to the shape specified.

5. Apparatus as defined in claim 4 in which the bottom of the notch is disposed above a line passing between the nips of said successive pair of rolls, and is directly in front of the side of the V which is substantially normal to the axes of the rolls with respect to the direction of approach of the sliver.

6. Apparatus as defined in claim 5 in which the condenser is mounted closely adjacent the nip of the pair of rolls to which the sliver is being delivered.

7. The combination with long draft fiber attenuating apparatus embodying a plurality of pairs of drawing rolls, of a condenser interposed between two successive pairs of rolls comprising a member having a V-shaped notch therein with one side of the V lying in a plane which is substantially normal to the axes of the rolls and the other side thereof inclined to said plane, and an inwardly disposed projection formed on the inclined side adjacent the forward end thereof with respect to the direction of approach of the sliver.

8. The combination with long draft fiber attenuating apparatus embodying a plurality of pairs of drawing rolls, of a condenser interposed between two successive pairs of rolls comprising a plate having a pair of upwardly disposed sides converging from rear to front of the condenser with respect to the direction of approach of the sliver and forming an upwardly opening V shaped notch disposed to receive the sliver, one of said sides having a forward edge which lies in a plane which is substantially normal to the axes of the rolls and the other side being inclined to said plane and having a forward edge which slopes downwardly from rear to front with respect to the direction of approach of the sliver, and a rounded bead on said forward edge of the inclined side disposed inwardly of the V notch, said first mentioned forward edge being substantially directly rearward of the bottom of the V notch with respect to the direction of approach of the sliver.

9. The combination with long draft fiber attenuating apparatus embodying a plurality of pairs of drawing rolls, of a condenser interposed between two successive pairs of rolls comprising a member having a generally V shaped notch therein defined by a side having its forward edge, with respect to the direction of approach of the

sliver, lying in a plane which is substantially normal to the axes of the rolls and a side inclined to said plane having a forward edge downwardly inclined from rear to front with respect to the direction of approach of the sliver, a rounded portion on said downwardly inclined edge disposed to contact the sliver, and a portion of said first mentioned forward edge being disposed rearwardly of said rounded portion and disposed to engage said sliver after it is engaged by the rounded portion.
